UNITED STATES PATENT OFFICE.

JAMES ELBERT BIRDSALL, OF PHILADELPHIA, PENNSYLVANIA, ASSIGNOR, BY MESNE ASSIGNMENTS, TO NATIONAL SHOE POLISHING MACHINE CORPORATION, OF NEW YORK, N. Y., A CORPORATION OF NEW YORK.

PEDESTAL FOR SHOE-POLISHING MACHINES.

1,246,031.

Specification of Letters Patent.

Patented Nov. 6, 1917.

Continuation (covering divisible subject-matter) of application Serial No. 687,529, filed March 30, 1912.
This application filed October 12, 1914. Serial No. 866,410.

To all whom it may concern:

Be it known that I, JAMES ELBERT BIRDSALL, a citizen of the United States, residing at No. 166 North Farson street, in the city of Philadelphia and State of Pennsylvania, have invented a new and useful Pedestal for Shoe-Polishing Machines, of which the following is a specification.

My invention relates to an attachment for shoe polishing machines in which brushes are mechanically moved about a fixed pedestal on which the foot of the user is resting, and this application is a continuation of my co-pending application for a shoe polishing machine filed March 30, 1912, Serial No. 687,529, and is partly shown therein.

The object of my invention is to provide a pedestal that will afford a foot-rest absolutely free from liability to injury to the foot resting thereon by reason of abnormal contact of any character with any of the movable parts of the shoe polishing machinery.

I attain this object by the construction illustrated in the accompanying drawings, in which—

Figure 1 is a plan view of the pedestal with a part broken away to show underlying construction; Fig. 2, a side elevation of the same, partly in section through the line $x-x$, Fig. 1; Fig. 3, a diagram of a system of the electrical connections when applied to an electrically driven shoe polishing machine; and, Fig. 4, a diagram of a system of the electrical connections when applied to a mechanically driven machine. It is to be understood that the circuits and appurtenances are merely diagrammatic to illustrate the course and effect of the electrical energy and that, in actual practice, the wires are to be properly insulated and so disposed as to best conform to the character of the shoe polishing machine to which applied.

Similar indices refer to similar parts throughout the several views.

The framework of my invention is a standard, 1, adapted to be suitably fixed to a convenient part of a shoe polishing machine, as, a bed-plate A. Yieldably mounted thereon is a pad, platform or foot-rest, 2, normally held by springs, 3, at a sufficient distance above the top of the standard to allow of an adequate depression of

the foot placed thereon. This foot-pad is purposely constructed to be sensitive and tractable to the pressure of the springs 3 and to the pressure of a foot above, so as to be susceptible of undulatory movements. So long as it possesses this characteristic, it is immaterial whether it be formed of a single sheet of rubber, leather or other pliable substance, or whether it consists of independent members. I have here shown it composed of four distinct segments, 4, each supported by a spring, 3, whereby the entire platform is uniformly and yieldably sustained, in the absence of any pressure thereon, above the standard, yet susceptible of uniform and complete depression when pressure or weight, as of a foot resting evenly thereon, is exerted from above. The character of this construction provides for the inevitable and independent rising under pressure from a spring, 3, of one or more of the segments, 4, should the foot pressure thereon be diminished, and, consequently, turning, twisting or rolling of the foot on top of the pedestal will be instantly accompanied by an elevation of the segment affected.

Suspended from each segment, as shown by the ball and socket joints, 5, and passing downwardly and freely through guide holes in the standard 1, is a rod, 6, which is thus adapted to rise and fall in unison with the undulations of the attached segment. Each rod terminates in a pointed tip, 7, adapted to make good electrical connection, when normally depressed, with the spring-contact 8, located immediately at short distance beneath. These members, 7 and 8, are parts of an electric circuit, 9 and 9^a, and are therefore insulated at 10 and 11, respectively, to prevent the possibility of any current reaching the pedestal or a foot thereon. The four sets of contacts, 7-8, are arranged in series in the circuit, 9-9^a, so that no current can pass unless all four of these contacts are closed. To cause and maintain this condition it is necessary that all four segments of the foot-pad be all the way down: in other words, the pressure on the foot rest must be regular and uniform throughout.

Fig. 3 illustrates the lay-out of the electric circuit adapted to operate in cases where the shoe polishing machine is actuated by its own individual electric motor, 12, while Fig. 105

4 illustrates the method of controlling a mechanically driven machine. This dual illustration is due to the fact that in the application of my device, the precise methods of attachment must vary according to the character of the mode of operating the shoe shining machine; that is to say, this machine may be run by an electric motor directly connected to its drive shaft, or it may operate by power from a main drive shaft.

10 In the former instance the four contacts are interposed between the main switch, 13, and the starting switch, 14, peculiar to the machine. That is, one lead, 9, connects one side of the switch 13 directly with the motor, and the other lead, 9^a, extends from the other side of the switch 13, in series, through the four contacts, 7—8, and the starting switch 14, necessitating a closed contact at 15 all these points, five in number in this illustration, to permit of the flow of any current through the motor, 12.

10 In the latter case, any convenient circuit may be utilized as current to effect the control of the mechanical power operating the 25 polishing machine. I have shown a battery, 15, as the medium of electro-motive force, and a friction clutch operated by a solenoid as the means of transforming the 30 electrical into mechanical energy. The lead, 9, connects one pole of the battery, 15, directly with the magnet, 16; the other lead, 9^a, extends from the other battery pole, in series through the four contacts, 7—8, to 35 the other side of the magnet. It is therefore necessary to close all four contacts, 7—8, to obtain a flow of current and to thus excite the magnet. When, however, these 40 points are closed and the magnet excited, the plunger core, 17, is drawn within, causing the lever 18 to throw a friction clutch, 19, into contact with both a gear 20, on the main power shaft, and a similar gear, 21, on the drive shaft of the shoe polishing 45 machine. It is therefore evident that unless this connecting clutch 19 is thus coupled with the clutches 20 and 21, no power is transmitted to the machine, and that this connection can only exist when the current is flowing 50 through magnet 16.

It follows, therefore, that if there be any 55 interruption of the electrical current, in either of the methods of installation described, the result will be the shutting-off of the motive power of the shoe polishing machine, and as any disarrangement, or improper position of the foot on the pedestal must result in opening the circuit, such disarrangement will instantly stop the action 60 of the shoe polishing machine. This stoppage will invariably attract the attention of the user and admonish him to re-adjust his foot to the normal and proper position on the rest, which being done, will re-establish 65 the current and cause the machine to resume

the operation. In short, so long as the foot is resting normally on the foot-piece, the machinery once started may operate and, assuming that any practical shoe shining machine is so constructed that no harm or 70 abnormal contact can happen to the foot while correctly positioned, safety is assured by my device; but, if, from distraction, curiosity or any other cause, the user raises, twists or otherwise misplaces his foot, the 75 motive power will be thereby instantly cut-off and all action of the brushes and other parts cease.

While my device serves to stop and to start a shoe polishing machine, it is not 80 essentially a starting and stopping attachment and must not be confused with such, the function of which latter is solely to set a machine going on its normal run. My device might be used time after time without 85 being called into active operation, and yet, with one nervous or restive individual, it might stop and start a machine several times during the process of blacking a single shoe. It is therefore essentially a safety device to 90 automatically act in the event of possible peril to the foot.

For the purpose of illustrating my invention I have described and shown in the accompanying drawings the form thereof at 95 present preferred by me, although it is to be understood that the various instrumentalities of which my invention consists can be variously arranged and organized and that my invention is not limited to the precise arrangement and form herein shown and described.

I claim:

1. In a safety device for a shoe polishing machine, a standard, a flexible member 105 yieldably supported thereon, and means actuated by the flexing of said member to control the supply of power operating a shoe polishing machine.

2. In a safety device for a shoe polishing 110 machine, a standard, a platform composed of divers segments superimposed thereon, a spring supporting each segment so as to leave an interval of space between said standard and said platform, whereby said 115 platform may be depressed in whole or in part by pressure, and means actuated by depression of said segments to control the supply of motive power to operate a shoe polishing machine.

3. In a safety device for a shoe polishing machine, a standard a flexible member yieldably supported thereon, an electric circuit adapted to control the motive power for a shoe polishing machine including make-and-break mechanism, and intermediate means to operate said make-and-break mechanism by the flexing of said member.

4. In a safety device for a shoe polishing machine, a standard, a platform composed 130

of divers segments superimposed thereon, a spring supporting each segment so as to leave an interval of space between said standard and said platform, whereby said platform may be depressed in whole or in part by pressure, an electric circuit adapted to control the motive power for a shoe polishing machine including make-and-break mechanism, and means to operate said make-and-break mechanism by depression and return of said segments.

5. In a safety device for a shoe polishing machine, a standard, a flexible platform yieldably supported thereon, an electric circuit adapted to control motive power for a shoe polishing machine, and divers pairs of electrical contacts in said circuit having one member of each pair so positioned with reference to said flexible platform as to open and close said circuit by the flexing of said platform.

10. In a safety device for a shoe polishing machine, a standard, a platform composed of divers spring-supported segments super-

imposed thereon, an electric circuit adapted to control motive power for a shoe polishing machine, divers pairs of electric contacts in said circuit and corresponding in number to the number of said segments, having one member of each pair so positioned with reference to one of said segments as to close and open said circuit by any depression and return thereof.

15. In a safety device for a shoe polishing machine, in combination, a pedestal comprising a standard with a resilient and undulant foot-piece thereon surmounted, an electric circuit, means, operable by inequality of foot-pressure on different portions of said foot-piece, to open said circuit and means whereby such opening of said circuit shall stop the motions of the shoe polishing machine.

20. JAMES ELBERT BIRDSALL.
